WHEEL COVER

George Albert Lyon, 13881 W. Chicago Blvd.,
Detroit, Mich.

Filed May 9, 1960, Ser. No. 60,497

Term of patent 14 years

(Cl. D14—30)

FIG. 1 is a perspective view of a wheel cover, showing my new design;

FIG. 2 is a substantially diametrical profile view through the wheel cover of FIG. 1; and

FIG. 3 is a front elevational view of an enlarged fragmentary portion of the wheel cover.

I claim:

The ornamental design for a wheel cover, substantially as shown.
